Application May 17, 1933, Serial No. 671,555

15 Claims. (Cl. 226—56)

The present invention relates to receptacles forming and filling mechanisms and embodies, more specifically, an improved mechanism by means of which receptacles may be formed with 5 a continuous operation, thus greatly simplifying the mechanism required for the forming operation.

In receptacle forming and filling machines now available the forming operation has been accomplished in an intermittent fashion by a mechanism which operates upon portions of material cut from a tube and is actuated intermittently to direct one end of each of the portions through a sewing machine to form a receptacle thereof. 10 The carrier for supporting the cut portions and moving the same through the sewing machine, receiving the cut portions from a stationary mechanism after applying the cut portions thereto, has heretofore necessarily been actuated intermittently. As a result of the intermittent motion of the carrier the mechanism for actuating the sewing machine has been of rather complicated nature and the entire mechanism has therefore presented difficulties in the manufacture and maintenance thereof. To overcome the disadvantages of forming receptacles with an intermittent motion the present invention has been 15 designed and an object is to provide a mechanism for forming receptacles with a continuous motion.

A further object of the invention is to provide a mechanism for continuously forming and filling receptacles with a suitable substance.

A further object of the invention is to provide 20 a mechanism for continuously forming, filling and closing receptacles.

A further object of the invention is to provide 25 a receptacle forming device having a carrier which moves continuously to effect the receptacle forming operations.

Further objects, not specifically enumerated above, will be apparent as the invention is described in greater detail in connection with the accompanying drawings, wherein:

Figure 1 is a view in side elevation showing a 30 machine constructed in accordance with the present invention and provided with a receptacle carrier which is actuated continuously.

Figure 2 is a view in end elevation looking from 35 the right in Figure 1, and showing the turning and filling mechanism, carrier and transfer mechanism, and driving elements therefor.

Figure 3 is a view in section, taken on line 3—3 40 of Figure 1, and looking in the direction of the

arrows, this view showing the carrier and transfer table which are driven continuously.

Figure 4 is an enlarged view in section, taken 45 on line 4—4 of Figure 1, and looking in the direction of the arrows, this view illustrating the cutting mechanism for severing portions from a tube or tubes of material.

Figure 5 is an enlarged view in section, taken 50 on line 5—5 of Figure 1, and showing the mechanism for securing strings to the bags.

Figure 6 is a partial view in end elevation showing 55 the construction of the clamp driving means of Figure 5.

Figure 7 is a view showing a receptacle formed 60 in accordance with the present invention.

Figure 8 is a view in horizontal section taken 65 through the staple driving arm and feed mechanism therefor.

Figure 9 is a view similar to Figure 6, showing 70 the manner in which the string lies in the grooves in the ends of arm, 93, this view being enlarged.

Figure 10 is an enlarged view in horizontal section 75 of one end of arm 93 showing the string lying in the groove and within the staple.

Referring to the above drawings, the frame of 80 the machine constructed in accordance with the present invention is shown at 10 and is provided with a power shaft 11 which may receive power from a gear 12, countershaft 13 and pulley 14, if desired. Power shaft 11 is provided with a driv- 85 ing pinion 15 which engages with a crown gear 16, secured to a transfer table 17. Table 17 is journaled at 18 upon a bracket 19 and carries a gear 20 which engages with a gear 21, mounted upon a stub shaft 22 (Figure 3). Stub shaft 22 90 is provided with two similar gears 21, 21^x, one of which is driven by the gear 20 as previously described and the other of which engages a gear 23 which is secured to a carrier 24. The number of teeth upon each of the gears 20, 21, 21^x and 23 is 95 such as to make the peripheral speed of the carrier 24 equal that of the transfer table 17. In as much as the diameter of the carrier 24 is less than that of the transfer table 17, the axis of the shaft 25 is offset with respect to the axis of shaft 18, a support 26 being provided to maintain the elements in proper relationship.

A cage 27 is oscillatably mounted upon shaft 25 and is provided with feeding mechanisms constructed in accordance with the copending application of Louis Hirschhorn and Hans Irmscher for Cloth feeding mechanism for combination tea bag machine, Serial No. 614,090 filed May 28, 1932. In as much as these feeding mechanisms form no part of the present invention they are indi- 100

cated in outline only and will not be described in detail herein. In the descriptive matter which follows, the present invention is described as embodied in a device utilizing twin feeding and filling mechanisms. Obviously only one feeding and filling mechanism may be used if desired and the invention is therefore not to be limited to the use of a plurality of such mechanisms.

The cage 27 is provided with an oscillatable feed head 28 upon which similar feeding mechanisms 29 and 30 are mounted in parallel relationship. These mechanisms are supplied with material from reels 31 and 32 (Figure 3) which are journaled upon brackets 34 mounted upon the frame 10. As the head descends, the ends of the tubes of material supplied from the reels 31 and 32 are moved over pairs of supporting fingers 33 which are mounted upon the carrier 24. After the ends of the tubes have been moved over the pairs of fingers 33 a cutting mechanism indicated at 34' in Figure 1 is actuated to sever portions of the tubes which are mounted over the supporting fingers 33 from the respective tubes supplied from the reels 31 and 32. The cutting mechanism will be described in greater detail hereinafter in connection with the construction shown in Figure 4.

During the downward movement of head 28 the cage 27 must be moving in the same direction and with the same speed as carrier 24. To effect such movement, an arm 35 (Figure 2) is provided on the cage 27 and is connected to a link 36 which is pivoted to one end of a crank arm 37 which is journaled at 38. Actuating arm 39 is connected to the arm 37 and provided with a roller 40 which is urged against the periphery of a cam disc 41 by means of a spring 42. Cam disc 41 is secured to a counter shaft 43 which is journaled upon the frame 10 and driven by a gear 44 which is driven by a gear 45, secured to the power shaft 11. The foregoing mechanism thus serves to oscillate the cage 27 and during the time that the cage is oscillating in the direction of rotation of the carrier 24 the speed of such oscillation equals the speed of rotation of the carrier 24.

Movement of the head 28 upon the cage 27 is effected by means of a saddle 46 which is pivoted to the sides of the head 28 and connected to a pitman 47 which is connected to an arm 48. Arm 48 is provided with a forked extremity 49 which is journaled between spaced brackets 50 secured to the frame 10. The free end of arm 48 is connected to a link 51 which is secured to an arm 52 of a bell crank lever which is journaled at 53 upon a stationary bracket 54. The bell crank lever formed by arm 52 is provided with an arm 55, the extremity of which is connected to a link 56 which is connected to a driving arm 57 secured to the power shaft 11. Driving arm 57 in rotating, thus causes the arm 52 to be rocked back and forth to reciprocate lever 48 in a vertical plane. The elements are so connected that during the following movement of cage 27 (the time during which the cage travels in the same direction as the carrier 24) the head 28 descends and thus places the ends of the tubes over the supporting fingers 33.

After the ends of the tubes are placed over the supporting fingers, the portions over such fingers are severed from the tubes by means of a cutting mechanism which is shown in detail in Figure 4. In the central plane of the cage 27, a pivot shaft 58 is provided. This shaft is adapted to lie midway between the pairs of supporting fingers 33, mounted upon the carrier 24, and oppositely extending cutter blades 59, 60, and 61 and 62 are

journaled thereon. Blades 59 and 60 are formed as a unit while blades 61 and 62 are formed as a unit to cooperate with the respective blades 60 and 59. Blades 60 and 62 are connected to similar links 63 which are pivoted at 64 upon a slide plate 65. Plate 65 is formed with a slot 66 which is adapted to receive shaft 25 and slide thereover and a slot 67 which is slidably mounted upon shaft 58. A spring 68 normally urges the plate 65 to the left as viewed in Figure 4 and thus tends to urge the cutter blades in a cutting direction. The blades are maintained in an open position by a trigger or pin 69 which is mounted upon the head 28 and is thus reciprocated vertically upon the cage 27. Plate 65 is provided with a notch or recess 70 which is adapted to receive the pin 69 and thus enable the latter to prevent sliding motion of the plate 65 during the time of engagement therewith. Plate 65 is moved into the position illustrated in Figure 4 by means of a roller 71 which engages a cam rail 72, mounted upon a stationary bracket 73. As the cage 27 is reciprocated in a direction contrary to the direction of rotation of carrier 24, the roller 71 engages the cam track 72 and moves the slide to the right as viewed in Figure 4. As the direction of rotation of the cage 27 is reversed the head 28 falls and pin 69 engages notch 70 to hold the cutter blades in open position. During continued following movement of the cage 27 the tubes are fed over the supporting arms. At the end of the following movement the head 28 is elevated and pin 69 is disengaged from notch 70 thus permitting the cutting operation to be effected. After the cutting operation has been completed the cage 27 is again moved in a direction contrary to the direction of rotation of the carrier 24 and the cycle of operations is repeated.

Each downward motion of the head 28 thus places severed portions of the tubes over adjacent fingers and the continuously rotating carrier 24 advances such portions through a sewing machine 74, as shown in Figure 2. The sewing machine thus sews the ends of the portions to form receptacles which are supported upon the arms 33 with the upper ends thereof closed. The continuous stitches of the sewing machine which extend between adjacent receptacles are severed by means of cooperating cutters 75 and 76 (Figure 1). These devices are mounted upon a stationary bracket 77 and are actuated by a link 78 which is pivoted to the arm 48.

From the cutting mechanisms 75 and 76 the carrier advances the arms and receptacles thereon under similar turning and filling tubes 79. These tubes are mounted upon a head 80 which is slideable upon cage 27, the head 80 being reciprocated by means of a saddle 81 which is connected by a link 82 to the arm 48. The tops of the tubes 79 are provided with hoppers 83 which are adapted to receive a substance from a suitable supply and direct the same into the tubes 79. During the following motion of the cage 27, the head 80 is lowered and the tubes 79 pass between the pairs of fingers 33. This motion effects a turning of the receptacles inside out and a simultaneous filling thereof, after which operation the filled receptacles fall into supporting cages 84, mounted upon the trans-fer table 17.

Supporting cages 84 are mounted upon the periphery of the table 17 and spaced in accordance with the spacing of the pairs of arms 37. In this fashion when the filled receptacles fall from

the carrier 24, corresponding adjacent supporting cages 84 receive these receptacles and cause the same to be moved with the transfer table 17 through a sewing machine 85. The sewing machine 85 sews across the tops of the receptacles and thus effects the closing thereof. To improve the appearance of the closed receptacles, the sewing machine 85 preferably forms an overlocked stitch, as illustrated in Figure 7.

From the sewing machine 85, the table 17 moves the closed receptacles into a stapling or clamping mechanism which is illustrated in detail in Figures 6, 8, 9 and 10. Mounted rotatably upon a stationary bracket 86 are spaced shafts 87 and 88. The shafts are provided with intermeshing gears 89, of equal diameter and pitch. One of the shafts, in the present construction shaft 88, is driven by a bevel gear 89 which engages a cooperating bevel gear 90 (Figure 1) which is driven by the power shaft 11. In this fashion, the shafts 88 and 87 are moved simultaneously. An arm 91 is secured intermediate its ends to shaft 87, the ends of the arm being formed with staple turning recesses 92. A similar arm 93 is secured intermediate the ends thereof to shaft 88 and the ends of arms 93 are recessed at 94 to receive staple driving plungers 95. Springs 96 normally urge the plungers outwardly and movement of the plungers is controlled by means of rollers 97 which engage the irregularly curved face 98 of a cam 99 which is mounted upon a stationary part of the machine.

Across each end of arm 93 is a horizontal groove 100 which is adapted to receive a string 101 upon which a plurality of tags 102 have been previously secured. A knife 103 is carried in each end of the arm 93 and may be actuated by the forward movement of plungers 95 to sever the string 101 upon the completion of a stapling operation. The string 101 may be frictionally held at the ends of arms 93 in any suitable fashion and a staple feeding mechanism 104 is provided to apply staples to the ends of the arm 93. This feeding mechanism may consist of a magazine 105 within which the staples are provided, a spring 106 normally urging the same to the right, as viewed in Figure 8. A plunger 107 is actuated to move the staples into the recesses 94. Figures 8 and 10 show the manner in which staples are inserted into the ends of the arm 93 and the manner in which the string lies across the staple. Figure 9 also shows the manner in which the string lies in the groove 100, preparatory to being secured to the receptacles. To accommodate such staple feeding operation, the bevel gears 89 and 90 may be mutilated to cause the arms 91 and 93 to rotate in a step by step fashion, or the staple feeding mechanism itself may move with the arm 93 during a portion of the movement thereof.

In Figure 3 a reel 103 has been illustrated as a means for supplying the string 101 with the tags attached thereto. In as much as the tag feeding mechanism forms no part of the present invention, further description herein is believed unnecessary.

From the foregoing, it will be seen that a mechanism has been provided by means of which receptacles are formed continuously. This mechanism is comparatively simple in construction and operation and functions to form, fill, and close receptacles in a continuous operation rather than an intermittent one as in existing constructions.

While the invention has been described with

specific reference to the accompanying drawings, it is not to be limited, save as defined in the appended claims.

I claim as my invention:

1. A receptacle forming device comprising a carrier, means to move the carrier, receptacle supporting means on the carrier, means to supply material to the supporting means, a sewing machine through which the supporting means moves the material to form a receptacle, and means on the supporting means to evert and fill the receptacle.

2. A receptacle forming device comprising a carrier, means to move the carrier continuously, receptacle supporting means on the carrier, means to supply material to the supporting means, a sewing machine through which the supporting means moves the material to form a receptacle, and means to engage the receptacle on the supporting means to evert and fill the receptacle.

3. A receptacle forming device comprising a carrier, means to move the carrier continuously, receptacle supporting means on the carrier, means to supply material to the supporting means, a sewing machine through which the supporting means moves the material to form a receptacle, a transfer means associated with the carrier and adapted to receive receptacles therefrom, means to move the transfer means at substantially the same speed as the carrier, and means to close the receptacles on the transfer means.

4. A receptacle forming device comprising a carrier, means to move the carrier continuously, receptacle supporting means on the carrier, means to supply material to the supporting means, a sewing machine through which the supporting means moves the material to form a receptacle, a transfer means associated with the carrier and adapted to receive receptacles therefrom, means to move the transfer means at substantially the same speed as the carrier, means to close the receptacles on the transfer means, and means to secure a string to the closed receptacles.

5. A receptacle forming device comprising a rotatable carrier having a plurality of receptacle supporting means spaced about the periphery thereof, means to rotate the carrier continuously, a cage oscillatably mounted upon the axis of the carrier, means to move the cage contrary to and in the direction of rotation of the carrier, means upon the cage to supply receptacle forming means to the carrier, and means to form receptacles of the receptacle forming means on the carrier.

6. A receptacle forming device comprising a rotatable carrier having a plurality of receptacle supporting means spaced about the periphery thereof, means to rotate the carrier continuously, a cage oscillatably mounted upon the axis of the carrier, means to move the cage contrary to and in the direction of rotation of the carrier, reciprocating means on the cage to advance a continuous tube of receptacle forming means toward the carrier, means on the cage to sever portions from the tube, and means to form receptacles of the portions of the tube on the carrier.

7. A receptacle forming device comprising a rotatable carrier having a plurality of receptacle supporting means spaced about the periphery thereof, means to rotate the carrier continuously, a cage oscillatably mounted upon the axis of the carrier, means to move the cage contrary to and

- in the direction of rotation of the carrier, reciprocating means on the cage to advance a plurality of continuous tubes of receptacle forming means toward the carrier simultaneously, means on the cage to sever portions from the tubes, and means to form receptacles of the portions of the tubes on the carrier.
8. A receptacle forming device comprising a rotatable carrier having a plurality of receptacle supporting means spaced about the periphery thereof, means to rotate the carrier continuously, a cage oscillatably mounted upon the axis of the carrier, means to move the cage contrary to and in the direction of rotation of the carrier, reciprocating means on the cage to advance a plurality of continuous tubes of receptacle forming means toward the carrier simultaneously, cutting members pivoted intermediate their ends upon an axis between the axes of the plurality of tubes,
- 20 a slide bar normally urging the members into a cutting direction, means actuated upon movement of the cage contrary to the direction of rotation of the carrier to move the slide bar and cutting members to an open position, means on the reciprocating means to hold the bar and cutting members in an open position, and means to form receptacles of the portions of the tubes on the carrier.
9. A receptacle forming device comprising a rotatable carrier having a plurality of receptacle supporting means spaced about the periphery thereof, means to rotate the carrier continuously, a cage oscillatably mounted upon the axis of the carrier, means to move the cage contrary to and in the direction of rotation of the carrier, reciprocating means on the cage to advance a continuous tube of receptacle forming means toward the carrier while the cage follows the movement of the carrier, means on the cage to sever portions from the tube while the cage follows the movement of the carrier, and means to form receptacles of the portions of the tube on the carrier.
10. A receptacle forming device comprising a rotatable carrier having a plurality of receptacle supporting means spaced about the periphery thereof, means to rotate the carrier continuously, a cage oscillatably mounted upon the axis of the carrier, means to move the cage contrary to and in the direction of rotation of the carrier, reciprocating means on the cage to advance a continuous tube of receptacle forming means toward the carrier, means on the cage to sever portions from the tube, means to form receptacles of the portions of the tube on the carrier, and means on the cage to fill the receptacles so formed.
11. A receptacle forming device comprising a rotatable carrier having a plurality of receptacle supporting means spaced about the periphery thereof, means to rotate the carrier continuously, a cage oscillatably mounted upon the axis of the carrier, means to move the cage contrary to and in the direction of rotation of the carrier, reciprocating means on the cage to advance a continuous tube of receptacle forming means toward the carrier, means on the cage to sever portions
- from the tube, means to form receptacles of the portions of the tube on the carrier, an evertng and filling tube slidably mounted on the cage, means to move the last named tube toward the carrier upon movement of the cage with the carrier, and means to move the said last named tube away from the carrier.
12. A receptacle forming and filling device comprising a continuously rotating carrier, means to supply receptacle forming means to the carrier, means to form receptacles of the said means, means to fill the receptacles on the carrier, a continuously rotating transfer table beneath the carrier, means to rotate the carrier and table at the same peripheral speed, receptacle receiving means on the table adjacent the periphery thereof to receive filled receptacles from the carrier, and means associated with the table to close the receptacles carried thereby.
13. A receptacle forming and filling device comprising a continuously rotating carrier, means to supply receptacle forming means to the carrier, means to form receptacles of the said means, means to fill the receptacles on the carrier, a continuously rotating transfer table beneath the carrier, the diameter of the table being greater than that of the carrier, means to rotate the carrier and table at the same peripheral speed, receptacle receiving means on the table adjacent the periphery thereof to receive filled receptacles from the carrier, means associated with the table to close the receptacles carried thereby, and means to secure a string to the receptacles.
14. A receptacle forming and filling device comprising a continuously rotating carrier, means to supply receptacle forming means to the carrier, means to form receptacles of the said means, means to fill the receptacles on the carrier, a continuously rotating transfer table beneath the carrier, the diameter of the table being greater than that of the carrier, means to rotate the carrier and table at the same peripheral speed, receptacle receiving means on the table adjacent the periphery thereof to receive filled receptacles from the carrier, and a stationary sewing machine associated with the table to sew the tops of the filled receptacles closed as the table rotates.
15. A receptacle forming device comprising a carrier, means to move the carrier continuously, receptacle supporting means on the carrier, means to supply material to the supporting means, a sewing machine through which the supporting means moves the material to form a receptacle, a transfer means associated with the carrier and adapted to receive receptacles therefrom, means to move the transfer means at substantially the same speed as the carrier, means to close the receptacles on the transfer means, a staple anvil, said anvil being positioned in such fashion that the transfer means moves receptacles against the face thereof, and means to drive a staple and string against a receptacle upon the face of the anvil.

WALTER M. INGRAM.
